INTERNAL COMBUSTION ENGINE

Harold Stewart Lamb, South Gate, Calif.

Application January 22, 1935, Serial No. 2,894

19 Claims. (CL 123—51)

My invention relates to the art of burning a combustible charge in an internal combustion engine of very high compression ratio and has as its special object a means to increase the initial 5 rate of flame propagation during the combustion cycle, thereby completing combustion in fewer degrees of crankshaft movement and giving more time for the expansion of the gases.

To accomplish this I employ a pressure-balancing mechanism which, by virtue of its movement may cause and control the combustion of the fuel charge in said engine. This pressure-balancing or oscillating mechanism is adapted to be moved by fluid pressures consisting of an explosion at one 15 end of its movement and an adjustable air cushion at the other end of its movement, the motion of the oscillator being under control so that the combustible mixture may be ignited or exploded by the heat of compression caused directly or 20 indirectly by said oscillating mechanism. The ignition temperature obtained thus, makes it possible to ignite the fuel charge without pre-ignition or detonation. The radius and weight of the oscillator together with the air pressure in the air 25 compression cylinder produce the right compression force to ignite the combustible charge under the most favorable conditions.

The principle of this operation is similar to that of the beam balance for laboratory work. The 30 fuel charge being ignited by the dynamic speed and precision of the oscillating mechanism is free to expand instantly. From this it will be seen that the combustion chamber is extremely flexible and may be adjusted to meet special requirements 35 while the engine is running.

The usual practice is to design the combustion chamber and machine the various parts to give a fixed clearance regardless of engine requirements. As a rule we ignite the fuel charge or 40 start it to burn before the piston reaches top center on its upward stroke. This is necessary because of the time required to complete combustion in fixed compression ratio engines and results in a wedge-like action, the crankshaft, with its 45 kinetic force, pushing the piston upward against the pressure of the burning combustible charge and reducing the size of the combustion chamber as it moves. This wedge-like action is too rough on some fuels and they rebel by detonating badly.

50 In my engine a variable air cushion moving with the oscillator and supplemented by spring action, produces a simple, yet positive, control for timing the ignition or compression pressure in the explosion chamber. The dynamic action of the oscillator is entirely spent in compression of the

combustible charge, not being limited by the rotation of the crankshaft.

Heretofore, engine designs intended to soften or reduce detrimental explosive pressures have depended on spring loaded devices of various designs which hold the pressure of compression and are intended to release the destructive pressures as they occur, but the trouble is that the detonation pressure rise is too fast for the sluggish mechanical movement of the devices to function. 5 It will be noted that I use springs in my oscillating mechanism but they serve to pull the oscillator away from the explosion chamber and not to hold it there.

The accompanying drawings and description 15 will serve to illustrate two practical uses to which I may choose to put my invention. The first is similar to a true Diesel, the pressure-balancing mechanism serving mainly to hold the maximum cylinder pressure to reasonable limits and reduce 20 the stresses on engine parts. The second engine is of the uniflow class and makes use of the oscillating mechanism in a different way from the first engine. The difference will be readily understood from the following:—

Fig. 1 is a longitudinal, vertical section through my improved engine viewed with the intake and exhaust side removed.

Fig. 2 is a transverse view of the engine, the cylinder block, crankcase section and included 30 parts being taken on line 1—1 and the head of the engine showing a section removed on line 2—2 of Fig. 1. The blower and fuel distributing pump are also shown in Fig. 2.

Fig. 3 is a section through the engine taken on 35 line 3—3 of Fig. 2 and shows the arrangement of intake and exhaust ports in the cylinder block, there being one intake and two exhaust ports 40 for each cylinder. The pistons 51 and 53 are shown as being in place for the intake and exhaust cycle. Other pistons in the engine are not shown.

Fig. 4 is a view looking down on the top of the engine as shown in Fig. 1.

Fig. 5 is a longitudinal view of the pressure 45 balancing lever.

Fig. 6 is a view of the pressure balancing lever taken at right angles to that of Fig. 5.

Fig. 7 is a vertical view of the pressure balancing lever shown in Fig. 5.

Fig. 8 is the left half portion of a vertical cross-section taken through an air compression cylinder of a modified form of my improved engine.

Fig. 9 is the right half portion of a vertical cross-section taken through the explosion cylinder 55

which with the cylinder of Fig. 8 makes the pair of cylinders I shall refer to later in my claims.

Fig. 10 is a side view of an intake manifold used to conduct the charge compressed in the crank-case of the air cushion cylinder over to the explosion cylinder. This manifold serves alternate pairs of cylinders in a four cylinder engine.

I have shown only two engines using the principles disclosed herewith but I do not wish to be limited to these only as the cylinders may be arranged radial type, V type or opposed type; also I may choose to make the air-cushioning cylinder smaller or larger than the explosion cylinder and the depth of the air cushion or the compression space between the two pistons may be changed to meet varying requirements.

Referring to the drawings by reference characters I have indicated my improved engine generally at 8 in Fig. 1. As shown, this engine is of the vertical-in-line type and includes a crank case 9 upon which a plurality of pairs of cylinders 10 and 12, 11 and 13 are mounted. A heavy crank-shaft 14 is mounted in bearings 15 which in turn are mounted in the crankcase webbing shown at 16. It will be noted that the bearings are provided with pressure lubrication through drilled oil passages 17.

Secured, by means of studs 18 and nuts 19, to the top of the cylinder block 20 is my pressure-balancing or oscillating mechanism shown at 21. This pressure-balancing or oscillating mechanism includes in detail the following parts:

The connecting rods 24, 25, 26 and 27 are hinged to the levers 22 and 23 at 33 by means of pins 32 as shown in Fig. 1 and Fig. 4. Pistons 28, 29, 30 and 31 are attached by means of wrist pins 16 to their respective connecting rods and form the crown of the combustion chamber in each cylinder. Soft metal discs 77 serve to prevent scoring of the cylinder walls by the wrist pins 16 as shown in Figs. 1 and 2.

Throughout this description I prefer to use the word "oscillator" with reference to levers 22, 23, or 94 and their attached connecting rods and pistons. Only one type of oscillating or pressure-balancing mechanism is shown in detail for the purpose of illustration; but I do not wish to be limited to this design since other designs have been found to be entirely satisfactory, such as the oscillator used with the type of cylinders shown in Figs. 8 and 9. Two coil springs are used to return each lever to its original horizontal position after the explosion pressure in the cylinder has forced the pressure-balancing mechanism piston to an extended position. A section through the spring housing cylinder 35 in Fig. 1 shows the coil spring 34 and piston 36 with wedge-shaped head 37 being pressed against the rollers 38. A plug 39 having a breather hole 40 is screwed into the cylinder at 41 to give the proper adjustment to the spring 34. In Fig. 1 the complete spring, piston and cylinder unit has been torn away at 42 in order to show more of the lever assembly. All friction surfaces of the pressure-balancing mechanism are lubricated through drilled holes 43, the oil being carried under pressure from the crank case 9 by pipe 44 and connected to the several parts at 45.

For each pair of cylinders in my improved engine a pressure-balancing mechanism is required. The arrangement of two pressure-balancing mechanisms with relation to each other is shown in Fig. 4 which is a vertical view of a four cylinder engine. For rigid construction and convenience in manufacture, the complete housing

for the pressure-balancing mechanism shown generally at 21 is cast integrally with the cylinder head plate 84, Fig. 4. The flange 85 is machined to receive a suitable cover, (not shown). In order to facilitate assembly of the pressure-balancing mechanism, the housing 21 separates at 86 as shown in Fig. 2.

The lever 22 is supported in bearings 46 and 47 as shown in Fig. 4. The spring 34, cylinder 35 and piston 36 shown in the cut-away section of 10 Fig. 4 are duplicated on the opposite side of lever shaft 48. The three views Fig. 5, Fig. 6, and Fig. 7 of the lever are shown to give a comprehensive idea of just what it includes. Drilled holes 43 are plugged at 43' to retain oil pressure. It will 15 be noted that the construction of the bearing journals 48 and 48' together with the enlarged portion 49 which holds the rollers 38 in position is extremely rigid. This is important as the pressure of exploding gases must be held by the 20 lever.

The operation of my improved engine is as follows: Fig. 1, cylinder 11, the combustion chamber 50 of piston 52 is charged with fuel and air which explode, forcing the piston 52 downward in the 25 cylinder. At the same time piston 29, being directly over piston 52 in cylinder 11, is forced upward. This delivers the full force of explosion to the pressure balancing mechanism previously described and in turn acts on piston 31. Piston 54 in 30 cylinder 13 moves simultaneously with piston 52 in cylinder 11 and so has the scavenging air compressed in the space 60. The piston 31, therefore, pushes the piston 54 downward by means of the air cushion thus formed. The next explosion 35 occurs 180 degrees of a revolution later in cylinder 10 with a balance of pressure being made with cylinder 12. Another 180 degrees of the revolving crankshaft brings the explosion cycle to cylinder 13, the pressure of which is balanced with that in 40 cylinder 11. The last explosion in the cycle occurs when piston 53 reaches the top of its stroke in cylinder 12, the pressure being balanced with cylinder 10. Thus we see that each cylinder goes through a pressure balancing cycle and an explosion cycle at 360 degree intervals or two revolutions of the crankshaft for each complete cycle of operation. Each piston is fitted with piston rings 59 to prevent the escape of compressed gas and to keep down excess oil.

Referring to Fig. 2 we have a view of cylinder 10 with piston 51 at the bottom of its stroke. Here, the induction of air and the expulsion of burned gas takes place. The blower 66, which is large enough to scavenge two cylinders simultaneously, delivers air into the manifold 65 thence to the cylinder at 61 through the passage 72 of the distributor casting 64. The velocity of the scavenging charge is great enough to strike the cylinder wall on the opposite side and then force its way upward. Thus it will be seen that the burned mixture is driven out of the cylinder at openings 62 on either side of the intake port 61. This part of the cycle will be readily understood by those experienced with the operation of two cycle engines.

A fuel pump is shown at 68 and is driven by a gear (not shown) housed in the case 67, Fig. 2. The fuel is forced through the pipe 69 and is sprayed into the cylinder at 70. Each cylinder has its own fuel system including pump, pipe line, and spray nozzle. The fuel is sprayed into the combustion chamber of each piston every other revolution of the crankshaft or every 720

degrees which is comparable to the spark timing of the conventional four cycle engine.

All exhaust passages in the cylinder block are indicated at 62 in Fig. 2 and Fig. 3. The casting 5 64 with its exhaust passage 71 and intake passage 72 is provided to simplify the construction of the intake and exhaust manifolds. An exhaust manifold is shown at 63.

The plate 73 shown in Fig. 2 serves as an exceptionally rigid mounting for the blower and fuel pumps and is secured to the crank case by cap screws 74. An engine support is shown at 75. The front end of crankshaft 14, Fig. 1 has a flange 82 with tapped holes 83, and is adapted to drive 10 the air pressure blower and fuel pump.

All wristpins 76 and wristpin keepers 77 are of conventional design. The connecting rods 55, 56, 57 and 58 have drilled oil passages shown in the cut away rod at 78. The crankshaft 14 also is 15 drilled for oil pressure shown at 79 in Fig. 1. Baffle plates 80 prevent the oil in the oil pan 81 from surging excessively. The oil pump being 20 of accepted design is not shown.

Referring to Fig. 8 we have a modified form of 25 my invention which is adapted to an engine of the uniflow 2 cycle class. The air cushion cylinder 88 is shown with piston 89 at the bottom of its stroke, having just uncovered the cylinder ports 90. The air cushion 91 holds piston 92 apart 30 from piston 89 and controls the movement of the oscillating mechanism shown generally at 87. Connecting rod 93 transfers the movement from piston 92 to the lever 94, the opposite end of lever 94 being connected to connecting rod 95 and in 35 turn to piston 96 in the explosion cylinder 97, Fig. 9. The exhaust port 98 is uncovered by the outward movement of piston 96 and closed by the inward movement which makes it necessary to provide piston 96 with a sufficiently long skirt.

40 A fresh charge is taken into cylinder 97 each revolution at intake port 99. Piston 100 uncovers intake port 99 on its downward stroke and compresses the charge within the crankcase 101. The crankcase section of the air cushion cylinder 88 also 45 is used to supply the cylinder 97. This is accomplished in a four cylinder engine by means of the manifold 102, Figs. 9 and 10. It will be noted that the manifold openings 103 and 104 are connected together by passage 105 and openings 106 and 107 are connected by passage 108. The throws of the crankshaft 109, Fig. 9 of my modified engine are in the same order as those of the engine at Fig. 1 and it is necessary to connect the crankcase sections together in alternate pairs 55 with a manifold of the type shown in Fig. 10.

The pistons 96 and 100 approach each other to form a combustion chamber at which point a threaded opening 110 is provided for a spark plug. In cases where a less volatile fuel is desired we 60 may use an injection jet instead of a spark plug. Compression ignition could be used or a second opening may be provided for a spark plug which would ignite the fuel sprayed by the injector.

The crankcase of the modified engine is divided, 65 having a section 101 for each throw of the crankshaft 109. The crankcase sections of the explosion cylinders have passages 111 which conduct the crankcase charge to said explosion cylinders through ports 99. A flange 112 on the outside of passage 111 is used to secure the manifold 102. The crankcase sections of the air cushion cylinders also have passages 111 but they are blocked off, to bypass into either passage 105 or 70 108 of the manifold 102. Each crankcase section 75 has a cylindrical type of valve 113 to admit the

charge at the right time. The manifold 114 is mounted on the cylinder valve housing 115 and a downdraft carburetor is used at 116.

The air cushion 91 in cylinder 88, Fig. 8 is supplied from a storage tank 117. In operation only 5 a small amount of air is used since the only escape is past the piston rings on pistons 89 and 92 or through the pressure regulator in housing 118. The conduit 119 leads to a valve in the housing 118 which may exhaust to the atmosphere or to the 10 storage tank 117. The purpose of the pressure regulator is to control the function of the air cushion. To increase the air cushion, a comparatively large valve 120 is provided as it is necessary 15 to change the pressure of the air cushion rapidly when the demand on the engine changes rapidly.

Extension or torsion springs are applied to lever 94 which constantly pull piston 92 against the air cushion 91. The stroke of the lever 94 may be shortened by increasing the air in the air cushion 20 91 and also increasing the spring tension on the lever 94. This reduces the dynamic force of the oscillating mechanism and produces a satisfactory control under ordinary conditions. However, in extremely adverse conditions we may find it 25 necessary to further reduce cylinder temperatures by improving the cooling system.

The movement of piston 89 and piston 92 in the cylinder 88 is unequal since they are not mechanically connected together. This makes it possible 30 to time the crankthrow of the air cushion cylinder so that piston 89 approaches piston 92 at just the right point in the cycle to obtain an effective bounce, driving piston 96 inward, compressing and igniting the combustible charge in the explosion 35 cylinder. The timing of piston 89 in the air cushion cylinder must be such that the oscillator piston 96 approaches piston 100 in the explosion cylinder at just the right time to compress and ignite said combustible charge. 40

Two advantages are gained by making the air cushion cylinder 88 larger than the explosion cylinder 97. First, the crankcase provides more air for scavenging and some supercharging. Second, a larger air cushion improves flexibility 45 of the oscillating mechanism.

A carefully worked out valve system might be applied to the cylinder 88 and the compressor 121 which supplies the storage tank 117 would be eliminated, but for the present, I recommend the 50 use of the compressor.

I prefer to start this engine with spark ignition. After the engine has been running a short warming up period the spark may be retarded in the usual way. The air pressure in the air cushion 55 cylinder is then adjusted to bring the explosion timing back to normal by means of the oscillator. This being accomplished there is no further need for spark ignition unless the revolutions of the engine drop to where the dynamic force of the 60 oscillator fails to compress the combustible charge sufficiently for ignition.

I am aware that, prior to my invention, improvements in the design of adjustable combustion chambers for internal combustion engines 65 have been made. With this in mind I have shown by drawings and description a device having certain novel virtues not obtainable heretofore and have set down the following claims with reference to said invention:— 70

I claim:

1. In an internal combustion engine having a pair of cylinders and a pressure-balancing mechanism which is movably responsive to the pressure of combustion in each cylinder, means to cause a 75

- combustible material to be supplied alternately to the cylinders in said engine, means to supply air to each of said cylinders, means to cause combustion of said combustible material and means to 5 exhaust said cylinders, the aforementioned pressure-balancing mechanism serving to cushion the explosive pressure in one cylinder with the air compressed in the other cylinder.
2. In a compression ignition engine a pair of 10 cylinders, means to supply air to said cylinders, means to supply fuel to one of said cylinders and means tending to cushion the explosive pressure of the burning fuel in one cylinder with the air compressed in the other of said pair of cylinders.
- 15 3. In a compression ignition engine having pairs of cylinders, means to supply air for compression each revolution and means to supply fuel during the compression of the air of each alternate revolution of each of said cylinders, means to 20 exhaust said cylinders and means tending to cushion the explosive pressure of said fuel with the air compressed in the other cylinder of said pair of cylinders.
- 25 4. In a compression-ignition engine having two cylinders associated by means of a pressure-balancing mechanism and having two pistons in each of said cylinders arranged to form an air compression chamber and a combustion chamber alternately when said pistons are in a contracted 30 position, a crankshaft and connecting rods, a blower to fill each cylinder with a charge of air and to scavenge the said cylinder of burned gases, a fuel spray nozzle adapted to spray fuel into said combustion chamber, one piston in each of 35 said cylinders being connected to said crankshaft the other piston in each of said cylinders being connected to the previously mentioned pressure-balancing mechanism.
- 40 5. In an internal combustion engine the combination of two cylinders associated together by a pressure-balancing mechanism having a piston extending into each of said cylinders and forming a part of the combustion chamber of each of said two cylinders, said pressure-balancing mechanism 45 serving to cushion the explosive shock in one cylinder with air compressed in the other cylinder, a second piston in each of the aforementioned cylinders, a crankshaft, connecting rods connecting each of last two pistons designated and the crankshaft, means to supply combustible material and air to said two cylinders and means to explode and scavenge the material, the explosion cycle and the air compression cycle alternating in each cylinder of said engine.
- 55 6. In an internal combustion engine, a crankcase having cylinders associated in pairs mounted thereon, a crankshaft in said crankcase, a piston in each of said cylinders, connecting rods connecting said pistons and said crankshaft, an inlet 60 and an outlet communicating with one of said cylinders, said inlet of one cylinder being connected to said crankcase and communicating with the section serving each cylinder, a carburetor, conduit means connecting said carburetor and said 65 crankcase, means to control the passage of fuel mixture through said conduit means, means to induce the combustible mixture from said crankcase into one cylinder of said pairs of cylinders while air from an outside source is being induced 70 into the other cylinder to maintain any pressure desired, and to form an air cushion to receive a portion of the explosive shock from the cylinder charged with a combustible mixture.
- 75 7. In an internal combustion engine including a plurality of cylinders associated in pairs and mounted on a crankcase, said pairs of cylinders having pistons moving simultaneously therein, said crankcase containing webs to form a cell under each cylinder of said engine, a valve mechanism operable to admit a combustible mixture to 5 the crankcase cells of each pair of cylinders, conduit means connecting said crankcase cells of each pair of cylinders with one cylinder of said pair of cylinders, the other cylinder taking in air through holes uncovered by the piston on its ex- 10 pansion travel in last mentioned cylinder, said pair of pistons compressing air in one cylinder and combustible mixture in the other cylinder, means to ignite the compressed combustible mixture and means tending to balance the pressure of the 15 burning combustible mixture with the pressure of compressed air and means to rotate the crankshaft in said engine by the pressure thus obtained.
8. In an internal combustion engine having a plurality of cylinders, there being an air compression cylinder associated with each explosion cylinder by means of a pressure cushioning mechanism, a crankcase, a crankshaft mounted in said crankcase, a piston in each of said cylinders, connecting rods connecting said pistons and said 20 crankshaft, said crankcase having webs to form a cell under each cylinder, a valve timing mechanism operable to admit air through said conduit means to each cell of said crankcase where it is compressed and thence discharged to an explosion 25 cylinder, said crankcase cell of each air compression cylinder being connected to the crankcase cell of the associated explosion cylinder, means to spray a combustible material into the explosion cylinder to give the pistons in said 30 cylinder a power impulse, the air compression cylinder having taken in air from a controllable source and forming an air cushion, means tending to cushion the explosive pressure in the explosion cylinder with the air cushion in said associated 35 40 air compression cylinder.
9. In an internal combustion engine having a pair of cylinders, means to supply air to one cylinder and a combustible mixture to the other, said pair of cylinders containing members associated with each other and movably responsive to the pressure in each of said cylinders, means to vary the pressure of air admitted to the air cylinder and thus change the compression pressure in the explosion cylinder. 45
10. In a hydrocarbon engine a pair of cylinders having two pistons in each cylinder, one piston in each cylinder being connected to the crankshaft by means of connecting rods, the other piston in each cylinder being connected to each other in a manner tending to equalize the pressure occurring in one cylinder with the pressure occurring in the other cylinder, means to supply a combustible mixture to one cylinder and air to the other of said pair of cylinders. 50
11. In an internal combustion engine, a pair of cylinders having a pressure-balancing mechanism which includes a movable member in each cylinder, means to produce power impulses in one cylinder and to compress air in the other cylinder, 55 means to vary the amount of air compressed in said cylinder thereby varying the compression pressure of the combustible mixture in the other cylinder. 60
12. In a hydrocarbon engine having a pair of cylinders associated with each other by a pressure-balancing mechanism, means to supply a combustible mixture to one cylinder and air to the other of said pair of cylinders, said pressure-balancing mechanism having members movably 70 75 charged with a combustible mixture. 75

responsive to the pressure occurring in each cylinder, thus reducing the tendency of the fuel to detonate during its explosion cycle.

13. In an internal combustion engine having an explosion cylinder and an air compression cylinder, means tending to balance the pressure obtained in the explosion cylinder with the pressure in the compressed air cylinder, said air compression cylinder providing pressure at the proper time to cause the pressure-balancing means to move, compressing and exploding the charge in said explosion cylinder.

14. In an engine having a combustion chamber and an auxiliary non-combustible fluid chamber, means to compress and explode and exhaust a combustible mixture in said combustion chamber, means to compress the non-combustible fluid in said auxiliary chamber, means tending to balance the pressure obtained in the combustion chamber with the pressure obtained by the compression of the non-combustible fluid, thus causing the pressure-balancing means to oscillate and explode the combustible mixture.

15. In a hydrocarbon engine having a pair of pistons moving in a pair of cylinders, means to supply and ignite and exhaust an explosive mixture in one cylinder and to supply a variable amount of air to the other cylinder of said pair of cylinders one piston in each cylinder being associated with each other in a manner tending to equalize the pressures obtained in each cylinder, the timing of the cycle of said air compression cylinder being such as will give maximum compression pressure in the combustion cylinder at the time ignition starts.

16. In an engine having an oscillating mechanism moving by means of fluid pressures in a pair of cylinders, said fluid pressures consisting of a combustible charge in one cylinder and a variable air pressure cushion held by spring tension in the other cylinder, the weight, and radius of the movement, of the oscillator together with dynamic energy imparted by the rebound from said air cushion and spring tension being calculated to

give sufficient momentum to compress the combustible charge to its ignition point, the timing of said ignition point having been determined by the cycle of the afore-mentioned air cushion cylinder.

17. In an internal combustion engine that includes an oscillating mechanism moved by fluid pressures and adapted to ignite a combustible mixture by virtue of dynamic energy imparted by said fluid pressures, the weight and radius of the oscillator of said oscillating mechanism being 10 such that it will compress and ignite said combustible mixtures, the control of the dynamic energy of said oscillating mechanism being accomplished with the aid of an air cushion moving with said oscillator.

18. In an internal combustion engine having a combustion cylinder and an air compression cylinder, an oscillating device consisting of a lever with a piston and connecting rod movably attached to each end, one piston extending into the 20 combustion cylinder to form a portion of the combustion chamber, the other piston extending into the air compression cylinder to form a part of an air cushion said oscillating device moving to compress and ignite a combustible charge in the combustion cylinder, the timing of combustion being 25 controllable by the cycle of said air compression cylinder which causes the afore-mentioned oscillating device to rebound after each explosion or combustion.

19. In an internal combustion engine having an oscillating mechanism which by virtue of its dynamic energy causes and controls the combustion of fuel in the combustion chamber of said engine, the oscillator of said oscillating mechanism being adapted to be bounced by fluid pressures, consisting of an explosion at one end of its oscillating movement and an air cushion at the other end of its oscillating movement, the dynamic energy thus imparted to said oscillator causing the 40 combustible mixture to be exploded or ignited by the heat of compression brought about by the bouncing action of said oscillator.

HAROLD STEWART LAMB.
